COMBINED ROTATING DISPLAY AND PRICE TAG
HOLDER ATTACHMENT FOR STORE SHELVES

Stanley S. Joseloff, 23 Soundview Drive, Westport, Conn.

Filed May 19, 1960, Ser. No. 60,651

Term of patent 14 years

(Cl. D1—3)

FIGURE 1 is a front elevational view of a combined rotating display and price tag holder attachment for store shelves, showing my new design, the radiating sectors on the cylindrical portion being shaded to indicate a contrast of color.

FIGURE 2 is a left-side elevational view thereof.

FIGURE 3 is a right-side elevational view thereof.

FIGURE 4 is a rear elevational view thereof.

FIGURE 5 is a top plan view thereof.

FIGURE 6 is a bottom plan view thereof.

I claim:

The ornamental design for a combined rotating display and price tag holder attachment for store shelves, substantially as shown.
